GEORGE A. WEINGARTNER, OF FORT THOMAS, KENTUCKY.

CUT-OFF MECHANISM FOR CIGARETTE MACHINES.

Application filed April 13, 1925. Serial No. 22,763.

Cigarette machines of the continuous rod type, have heretofore been limited in the output to be derived therefrom by the vibration of the cut-off mechanism, for the reason that this vibration is transmitted to the main frame of the machine. In any cut-off mechanism for such machines the cut-off knife must traverse with the cigarette rod during the time of the cut. In general, such a cut-off mechanism consists of a reciprocating rod guide divided transversely to the axis thereof for the passage of the cut-off knife. The knife is usually a rotating disk of steel sharpened on the periphery. In the majority of such mechanisms the frame carrying the knife is rotated through a circular orbit the plane of which is at a right angle to the plane of the knife disk, and the plane of the knife disk is furthermore at a right angle to the axis of the cigarette rod, and consequently to the axis of the rod guide since the axis of the guide must coincide with the axis of the rod while it is passing therethrough. The rotary movement of the carrier frame and the reciprocating movement of the rod are so co-related that the following series of operations is accomplished in unison. The rod guide is reciprocated forward and backward in the direction of the axis of the rod which is traversed at a uniform speed through the rod guide by the main mechanism of the machine and with which main mechanism the movements of the cutting mechanism are timed by the use of positive driving means. During one stroke of the rod guide it is moving in the same direction as the rod itself. During a portion of this stroke, the rotary motion of the carrier frame causes the sharpened edge of the knife to pass through the opening in the rod guide and sever the rod, cutting off a cigarette. It is obviously desirable that the movement of the rod guide and the movement of the knife in a direction parallel to the direction of the movement of the guide, should closely approximate that of the rod itself. Any lack of uniformity of the two movements, such that would cause the traverse of the rod guide to be faster or slower than the traverse of the rod, would cause the direction of the cut to depart from a right angle to the axis of the rod. In the case of the type of cut-off mechanism in which the reciprocation of the guide is produced directly through a connection of the rotating mechanism of the knife carrier, as by means of a connecting rod or substitute therefor, the movement of the guide and the knife in a direction parallel to the movement of the rod is at no time uniform, but takes on the character of the movement of a piston in a reciprocating engine. In mechanisms of this type, heretofore in general commercial use, the passage of the knife through the rod during the process of severing the same, has been accomplished by the movement of the knife alone. This is accomplished by so locating the center of the orbital path of the knife carrier that the distance between this center and the center of the axis of the rod guide, measured along the plane of the orbit traversed by the carrier and in a direction at right angles to the axis of the rod guide, is less than the radius of the orbit by slightly more than half the diameter of the cigarette. The movement of the knife during the process of severing the rod must take place during the time when the knife and its carrier frame are passing through a certain arc of its orbital path. The extent of the movement of the knife subtended during the severing of the rod is, therefore, the versed sine of this arc. The smaller the angle subtended by the arc, the more uniform the speed of the travel of the knife along the chord of the arc and the smaller will be the variation between the traverse of the knife and the traverse of the rod. The shorter the movement of the knife at a right angle to the axis of the rod, the shorter will be the versed sine of the cutting arc, and hence both the included angle of the arc itself and the radius of the orbit of the knife carrier will be correspondingly shorter. The smaller the radius of movement of the knife carrier, the less will be the inertia of the carrier and the parts that move with it. Furthermore, the smaller the radius of the orbit, the more easily the parts moving therethrough may be balanced effectively. By reduction of the inertia of these parts, the greater will be the speed at which the cut-off mechanism may be operated without imparting objectional vibration to the balance of the machine, and the greater will be the output that may be obtained therefrom.

The main object of this invention is to produce a cigarette cut-off mechanism so constructed that the objectional inertia effect may be reduced to a minimum and thereby increase the speed at which it will be practical to run the machine. Another

object of my invention is to produce a device in which the knife and its carrier will traverse a circular orbit of small radius as compared to the radii of the orbits of similar devices in commercial use, and therefore 5 reduce the inertia effect by reducing the amplitude of movement of the parts. Another object of my invention is to produce a device wherein the angle of the knife carrier orbit during which the severing of the rod is accomplished, is sufficiently small to cause the knife to traverse at a substantially uniform speed during the operation of severing the rod, and in the accomplishment of 10 this object I have produced a design such that the arc traversed by the knife carrier during the severing of the rod and the receding of the knife from the path of the rod shall be not greater than that subtended by 15 an angle of sixty degrees. Another object of my invention is to reduce the parts of the knife carrier which are required to traverse the carrier orbit, to the smallest possible number and extent, and to so dispose 20 of these parts that they may be balanced with small weights or the equivalent of balancing weights. Another object of my invention is to produce a device wherein the movement of the knife during the cutting of the rod 25 is very short, thereby shortening the versed sine of the arc of the orbit traversed by the carrier during cutting, and the necessary radius of the carrier orbit. Another object 30 of my invention is to produce a device whereby the rod may be severed by moving the rod into the path of the knife during the cutting thereof, and thereby reduce the movement of the knife and its carrier, thereby accomplishing the cutting 35 movement by reciprocating the comparatively light rod guide rather than the heavier combination of the knife and its carrier parts, thereby transferring the greater part of the cutting movement to a light part 40 with small inertia, hence reducing the cutting movement of the heavier parts with their much greater inertia. Another object 45 of my invention is to simplify the adjustment of the device to set it for the accommodation of cigarettes of various lengths, by 50 making this adjustment with but one adjusting screw. With these and other objects not specifically mentioned in view, the invention 55 consists in certain combinations, constructions and parts which will be hereinafter described and specifically pointed out in the 60 claims hereunto appended.

In the accompanying drawings which 65 form a part of this specification:

Fig. 1 is a sectional elevation of a device 70 constructed in accordance with the invention, the section being taken along the line 1-1 of Fig. 2.

Fig. 2 is a front elevation partially in 75 section along the axis of the rod guide 42-

43 and along the line 2-2 of Fig. 1 and with the carrier removed.

Fig. 3 is a sectional plan view of the forward portion of the device taken along the 80 line 3-3 of Fig. 2.

Fig. 4 is a partial rear elevation showing 85 the cam for lifting the rod guide and the rear arm of the bell-crank lever for transmitting motion from the cam to the rod guide.

Fig. 5 is a section of the main driving 90 shaft taken along the line 5-5 of Fig. 1, and showing the parts in the relations they assume when the adjustment is set for an orbit of maximum radius, and for cutting off a cigarette having the greatest length within the capacity of the machine.

Fig. 6 is a section along the same line as 95 that of Fig. 5, but with the parts adjusted for smaller orbit than in Fig. 5, and hence for a shorter cigarette.

Fig. 7 is an edge view of the cutting knife 100 together with a diagram showing the relations of the carrier orbit, and the lift of the rod with the guide.

Fig. 8 is a diagram on a greatly enlarged 105 scale, showing the path of the edge of the knife during the cut, and the relative positions of the rod and the cutting point of the knife at the various progressive steps; 110 first during the process of severing the rod, and second while the knife is receding from the cut.

In carrying the invention into effect 115 there is provided a knife, a shaft therefor upon which the knife is mounted, and a knife carrier containing the bearings for the knife shaft and in which bearings the shaft is mounted. Attached to knife carrier is a shaft eccentrically mounted in the main driving shaft of the device to rotate 120 the carrier in an orbital path. There is further attached to the carrier a cross-head designed to maintain the axis of the knife shaft at all times parallel to the axis of the rod guide. Means for revolving the knife at about three times the speed of the main driving shaft is provided. The rod guide is attached to the cross-head for giving the rod guide a reciprocating motion along the path of the rod, and a mechanism consisting of a face cam and bell-crank lever is provided for lifting the rod into the path of the knife during the cutting. Means are provided for adjusting the radius of the orbit, and with 125 it the time of the stroke of the rod guide to provide for the various lengths of cigarettes within the capacity of the device.

In the preferred construction, as illustrated 130 in the accompanying drawings, the mechanism for producing an orbital movement of the knife carrier consists of a main driving shaft operatively connected to the main mechanism of the machine of which the device forms a part, and timed with the

machine, and an eccentrically mounted carrier shaft so designed that the eccentricity of the path of the carrier shaft may be varied at the will of the operator from zero to the full capacity of the machine, a cigarette 90 mm. long being the full capacity of the device shown in the drawings. The particular form of the device which has been selected to illustrate the invention is 10 but one of the many concrete embodiments of the same. Therefore, the invention is not to be restricted to the exact details of the particular structure selected as an illustration thereof and shown and described 15 in these specifications and the accompanying claims.

Referring to the drawings, 6 indicates the main frame of my cigarette cut-off mechanism which may be attached to bed 01 20 a cigarette machine by any suitable and convenient means, and it is in this frame that the majority of the parts of the device are mounted. Attached to the front of the frame is a cover 7, held in place by means 25 of screws 8. In the rear of the device is a second cover 9, hinged to the frame 6 at 10 and held in position by means of the spring catch 11. A main driving shaft 12 is mounted in the frame 6 through the medium of 30 the ball bearings 13-13, and is therefore free to revolve therein. Upon the rear end of the shaft 12 is a driving gear keyed thereto, which is positively driven from the mechanism of the machine of which this device forms a part. Passing entirely through 35 the shaft 12, with its axis parallel to, but not coincident with the axis of the shaft 12 is an intermediate shaft 15 which is free to rotate within the shaft 12, but is made a 40 snug running fit thereto. The intermediate shaft 15 is provided with a bore 16, the axis of the bore being parallel to, but not coincident with the axis of the intermediate shaft 15. Within this bore is mounted the 45 knife carrier shaft 17 in the bearings 18-18, and attached to the front end of this shaft is the knife carrier 19, and mounted therein upon the bearings 20-20 is the knife shaft 21, and mounted upon the shaft 21 is 50 the knife arbor 22, carrying the knife 23 clamped in place by means of the washers 24-24 and the nut 25. Upon the front end of the intermediate shaft 15 is bevel gear 26 attached to 15 by means of the screws 27. 55 This gear is so mounted that its center is in line with the axis of the bore 16 and hence with the axis of the shaft 17, and it is in mesh with the knife shaft pinion 28 mounted on the end of the knife shaft 21. 60 Attached to the knife carrier 19, and forming a part thereof, is a cross-head guide 29 and in grooves, provided therein are two rows of balls 30, forming a ball-bearing runway for the vertical leg 31 of the cross- 65 head comprised of this member and the

horizontal leg 32 of the cross-head. The leg 32, in its turn is guided and constrained to travel in a horizontal direction only by means of the guide 33 attached to the cover 7, and running on the ball-bearing guide-way comprised of the balls 34, traversing in grooves provided therefor in the guide 33 and in the horizontal leg 32 of the cross-head.

For the purpose of supporting the cigarette rod to be severed by the knife 23, a guide for the rod is provided. The cigarette rod moves and must be moved in a substantially straight line. In order that it may co-operate with the knife, the guide must move 75 in co-ordination with the movement of the orbital movement of the knife carrier and the knife. This movement, as provided for in the device being described, is a combination of a short reciprocating movement, and 80 a short vertical movement during the time that the rod guide is traversing in the same direction as the rod. In order to provide for exact co-ordination of the movements 85 of the knife and the guide, the latter is 90 so constructed that it derives its horizontal movement from the same source as the source of the orbital movement of the knife carrier and the knife, that is, it derives its movement from the axis of the orbital movement 95 of the carrier. The guide proper is comprised of two tubes in alignment and designed to stand normally in line with the path of the cigarette rod as it is passing from the machine, the leading tube being marked 100 35 and having the usual flared entrance 36; and the following tube marked 37, and having the slightly flared entrance 38, the two tubes being slightly spaced apart to provide room for the passage of the knife between them. The leading tube is surrounded with another tube 39 provided with an extended lip or cutting ledge 40, preferably made of hardened steel with a polished surface, and against which the cutting edge of the knife bears lightly in order to give a shear cut when severing the rod. The rod guide together with the ledge are both mounted in the guide holder 41, attached by the bolts 42 to the guide carrier 43, the bolts 110 115 being passed through the slot 44 provided in the part 43. This slot permits a vertical adjustment of the rod guide to compensate for reduction of the diameter of the knife 23 due to wear and sharpening. Attached to the rear of the rod carrier 43 are a pair of grooved steel guides designed to receive the balls 30 and to slide in a vertical direction on the vertical arm 31 of the cross-head. 120 Horizontally disposed in the carrier 43 is a slot 45 and in this slot is a roller 46 adapted to traverse therein, being fitted snugly but freely to the slot. The roller 46 is mounted on the pin 47, and the pin is attached to the 125 end of the lever 48, the lever forming one 130

member of a bell-crank comprised of the levers 48, and 49 and the shaft 50, the levers being pinned to the shaft 50, which is mounted in the bearings 51 and 52 forming a part 5 of the frame 6. The upper end of the lever 49 carries a pin 53 mounted therein, and on this pin is mounted a roller adapted to traverse the groove 55 provided in the cam 56. The cam 56 is attached to the gear 14 by means of the bolts 57, the bolts passing through the circumferential slots 58 in the gear and indicated by dotted lines in Fig. 4, the slots permitting of angular adjustment of the cam with relation to the gear, and the 10 parts attached to the gear. For the greater portion of the circumference of the cam 56, the groove 55 is concentric with the center of the cam, and no movement is given to the lever 49, during the time this portion of the 15 groove is passing over the roller. For approximately thirty degrees of the circumference of the cam, the slot is moved radially outward passing around the node 59, and the roller 54 and the lever 49 are swung outwardly away from the center of the cam, the movement of the lever 49 being transferred through the shaft 50 to the lever 48, raising the outer end of this lever, and imparting this movement to the carrier 43 through the 20 medium of the pin 47 and the roller 46. This vertical movement of the carrier raises the rod guide attached thereto and this movement is so timed that it begins just as the knife 23 has approached the lower portion 25 of its orbit, the lift of the rod guide beginning at the instant the edge of the knife 23 has reached the upper side of the opening in the guide, and the start of the cut to sever the rod occurs during this period in the cycle 30 of operations. The position of the knife with relation to the rod at this precise moment in the cycle is shown in Fig. 7, in which the orbit traversed by the cutting edge of the knife is indicated by the dotted circle 35 60, and upper and lower edges of the rod by the broken lines 61 and 62 respectively.

In any cigarette machine it is necessary to so time the cut-off mechanism with relation to the movements of the other mechanism of 40 the machine that the cycle of operations of the cutting mechanism is completed during the time that the cigarette rod has traversed a distance equal to the length of the cigarette for which it is set. The length of the 45 average cigarette is $2\frac{3}{4}$ inches or 70 mm., and cigarette machines are customarily designed for lengths of from 65 to 85 or 90 mm. The means provided for adjusting the mechanism to suit the requirements of cigarettes of various lengths includes an adjusting screw 15' fitted in a suitable smoothly bored opening provided in the main shaft 12, and held from longitudinal movement 50 relative to the shaft 12 by the screw 16'. The threads of the screw 15' mesh with the 55

sector 15'' of a worm gear cut in the periphery of the intermediate shaft 15. The cut-off mechanism shown in the accompanying drawings is designed for lengths of zero to 90 mm., although the design is adaptable to cigarettes of any length. In all the figures with the exception of Fig. 6, the mechanism is shown as adjusted for a cigarette of the maximum length or 90 mm., for the reason that this adjustment is that which would tend to produce the greatest distortion of the cut from a right angle to the axis of the rod. The relations of the parts shown in Fig. 6 are those assumed when the mechanism is adjusted for cigarettes 65 mm. long. The device is so designed that the radius of the orbit is one-sixth of the length of the cigarette for which the machine is set.

The successive positions of the knife and the rod, during that part of the cycle of the cut-off mechanism involved in the severing of the rod and during that portion of the cycle during which the knife and the rod are receding from the cut, are shown on an enlarged scale in Fig. 8. In this figure, a fragment of the knife is shown at 23' in the position the knife should occupy just as it starts the cut, and just at beginning of the lift of the rod guide through the medium of the cam 56 and the intervening levers 48 and 49, the successive positions of the knife during the cutting of the rod and at intervals of two degrees of the circular path of the cutting point being shown by the points 23^a, 23^b, etc., to 23ⁱ indicated by broken lines, with the points resting on the circular arc 60 representing the orbital path of the cutting point. The successive positions of the knife during the downward stroke continued after the knife has passed through the rod are indicated by the points 23^k to 23° inclusive, and the remaining points show the successive positions of the knife during the time when the knife and the rod are receding from the cut. The vertical lines 63-63 on the upper side of the base line 64 are projected from the points 23^a, 23^b, etc., normal to the base line, the space between them indicating the intervals measured in a horizontal direction between the various successive positions of the cutting point of the knife. Below the base line, and also normal thereto, are a series of vertical lines 65-65 equally spaced to indicate the successive positions of the rod during the cutting operation, assuming that the speed of the rod is uniform. The differences between the widths of the spaces between the lines 63-63 above the base line 64, and the spaces between the lines 65-65 below the base line show, on this large scale how closely the point of the knife follows the rod during the cut. Starting at the point y where the knife point 23' meets the orbit at path 60 (in Fig. 8) and swing- 130

crossing the lines 63-63 extended beyond and above the orbital path, the intersections being at the successive points occupied by the rod guide as it is lifted during the cut, 5 the height of the lift, at any step in the cycle, being measured from the line $x-y$ which is the chord of the arc $y-z$. This arc is the path traversed by the cutting point of the knife during cutting and receding combined. 10 The depth of the cut, at any one point, is the sum of the lift of the rod guide measured from the line $x-y$ upwardly and the distance of the point of the knife blade below the line $x-y$. In the lower portion of the 15 figure I have indicated a cigarette rod on an enlarged scale occupying the space between the lines 61' and 62'. Across the rod I have drawn a straight line 66 at a right angle to the axis of the rod, and across this 20 line I have drawn the short lines 23^a, 23^b, etc., to indicate the successive vertical positions of the cutting point 23' of the knife blade with relation to the rod, these positions corresponding to the positions 23^a, 23^b, etc., 25 indicated on the orbital path 60. At the right of line 66 I have drawn a curved line 67 cutting the lines 23^a, 23^b, etc., at the actual points occupied successively by the cutting point of the knife edge 23', these points 30 being indicated by the intersections of the lines 23^a, 23^b, etc., with the curve 67. The space between the line 66 and the curve 67 shows the actual departure from a truly right angle or square cut made by the knife 35 in my cutting off mechanism. The deflections are laid off as closely as possible to scale, the deflection as shown in the drawing being the actual deflection magnified about eight times. The maximum deflection 40 from a true right angle cut is experienced when the mechanism is adjusted for cutting off cigarettes of the maximum length of 90 mm., the distance measured horizontally between the lines 66 and 67 being greatest at 45 the point 23' or when the knife is just half way through the rod. This deflection for a 90 mm. cigarette is but .00533 inch, and the mean angle of the deflection from a normal to the axis of the rod is $1^{\circ} 43' 20''$, an 50 angle of cut which is much less than that secured by the cutting mechanism of any other cigarette machine in actual use. The corresponding deflections for shorter cigarettes are proportionately less. It will be 55 noted by observation of the positions of the lines 63 and 65 during the various successive steps in the cycle after the cut has been completed, that the knife is, at all times, in advance of the rod during the time the knife 60 and the rod are receding from the cut. Hence there is no time during this period of recession that the knife is crowding back against the rod.

In the operation of my improved cut-off mechanism for cigarettes, the only adjust- 65

ments required are the variation of the radius of the knife carrier orbit, and the position of the node 59 of the cam to comply with the requirements of the length of the cigarette and the adjustment of the height 70 of the rod guide holder 41 with relation to rod carrier frame 45 to compensate for the wear of the knife. To adjust the radius of the orbit it is required to first loosen the bolts 57 and then to turn the adjusting 75 screw 15, to rotate the intermediate shaft 15 until the radial distance between the centers of the shafts 12 and 17 equal the radius of the required orbit, this radius being equal to one-sixth of the length of the 80 cigarette. Rotation of the shaft 15 causes the cam 56 to rotate a corresponding amount, and it is but necessary to tighten the bolts 57 to ensure the adjustment being maintained. Graduations B on the face of the 85 cam and a registration arrow A on the face of the gear 14 show the operator when the cam is set properly, and corresponding graduations at C near the center of the cam indicate when the shaft 15 has been set properly. The setting of this adjustment is not very exacting as a slight variation from the 90 theoretically correct positions of the cam and the intermediate shaft will make no 95 appreciable difference in the results.

The operation of the device during the process of cutting the rod is as follows: The proper gears are interposed between the driving gear 14 and the mechanism of the cigarette machine to so time the cut-off 100 mechanism that it will make one complete cycle or turn of the shaft 12 while the rod is traversing the length of the cigarette. The knife carrier turns through an orbit determined by the setting of the device as 105 already explained, the shaft 17 being free to revolve in the shaft 15 and the knife carrier being constrained from rotating on the axis of the carrier shaft 17 by the cross-head 31-32, the shaft 17 must make one revolution on its axis for each revolution of the mainshaft 12. This produces a turning movement between the gear 26 and the pinion 28, rotating the shaft 21 and the 110 knife 23 attached thereto. Restrained from turning around the axis of the shaft 17 and guided by the cross head 31-32, the plane of the knife 23 is at all times at a right angle to the axis of the rod. Therefore 115 the only variation from a right angle that is possible for the cut is that due to variations between the speed of rod, which is uniform, and the speed of the knife in a direction parallel to the axis of the rod during cutting. At any point in the orbital path traversed by the knife point, the horizontal distance from the line $x-y$ is determined by multiplying the radius of the orbit by the 120 sine of the angle between the radial line passing through the knife point and the 125

line $x-y$. The depth of the cut produced by the downward movement of the knife during this portion of the orbit is the versed sine of the angle of the orbital path at the 5 position when the knife meets the rod, or the distance $x-x'$, Fig. 8. In order to pass the knife through and beyond the rod a distance sufficient to ensure a clean cut, the radius of the orbit must be large or the angle 10 passed through during the cutting operation must be large. Customarily the angle of the orbital arc passed over by the knife during the cutting operation is 45° instead of 30° as employed in my invention. This 15 would require that the radius of the orbit shall be fully two and one-half times the radius of the orbit required in the present device when using but 30° . The use of 45° makes a considerably greater departure from 20 a right angle or square cut than when but 30° of the orbit are employed for this purpose. In any cigarette machine the rod is always whipping back and forth and a slight deflection of the rod from its normal path 25 is of no consequence. Hence, such a deflection of the rod to meet the knife and to pass the rod across the path of the knife to sever it cannot harmfully affect the product or interfere with the operation of the cut-off 30 mechanism for the reason that the amplitude of the deflection of the rod required to cut it is less than the amplitude of the normal whip. Raising the rod and passing it across the path of the knife to sever the rod I 35 believe to be new in the art. Causing the knife and the knife carrier to pursue an orbital path during and between the operations of severing the rod is old and a method of causing the knife carrier to pursue such a 40 path is described in the expired patent to Bagguley No. 647,174, but the means of causing the knife carrier to pursue such a path, and the method of varying the radius of the orbit I have described in this specification, I believe to be new and novel.

While the manufacturer of the device herein described has a choice of several metals from which it may be manufactured to advantage, I believe that the rotating parts 50 of the knife carrier, and especially those not subject to frictional wear may be made to best advantage from an alloy of aluminum such as duralumin, and the runways for such parts as the balls 29 may be made of strips of tempered steel attached to the aluminum. The various parts of the rod guide as well as the levers 48 and 49 and the center structure of the cross head may be 55 of a light alloy. Attention is called to the fact that the combination of the three shafts 60 12, 15 and 17 are in substantially perfect balance regardless of the position to which they may be adjusted. Certain of the parts such as the knife carrier and the gear 26 65 may be counterbalanced for the mean radius

at all times, or the counterbalance may be varied with the setting to be correct in any radius. As the mean radius of the orbit is but $12\frac{1}{2}$ mm. and the variation therefrom for the longest and the shortest cigarette is 70 but $2\frac{1}{2}$ mm. or 20%, a fixed counter balance should serve the purpose. Such a counter balance may be effected by removing a portion of the rim as indicated at 56'. As the only reciprocating parts of the device, 75 the cross head and the rod guide with its carrier, are comparatively light, and since all parts of the knife carrier are rotating, the operation of the device at speeds from fifty to one hundred per cent more than is 80 possible with the cutters now in commercial use is thoroughly practical. This would mean an output of from 1,200 to 1,600 cigarettes per minute, or a saving of a considerable outlay in machines, a saving in 85 floor space, and in the cost of attendance and upkeep for a unit production of cigarettes.

As the operation of the device is obvious to those skilled in the art, no explanation 90 thereof, in addition to that given during the description of the parts and their functions, is necessary.

I claim:

1. The combination with a circular cigarette cut-off mechanism, of a driving shaft therefor, a carrier for the shaft, and means for producing a continuous movement of the knife and the carrier in an orbital path, said means including a main cross-head 95 frame, guides therefor, said guides providing means for so constricting the movement of the carrier that it cannot revolve, but must follow a path lying in a plane at a right angle to the axis of the rod guide, a carrier shaft attached to said carrier, a main driving spindle, said carrier shaft being supported in bearings in said main driving shaft, the axis of the carrier shaft and said main driving shaft being parallel one to the 100 other, and said carrier shaft being eccentrically mounted in said main driving shaft. 110

2. The combination with a circular cigarette cut-off knife, of a driving shaft therefor, a carrier for said shaft, means for producing a continuous movement of the carrier in an orbital path, said means including a series of three shafts nested, the axes of the three shafts being parallel one with the others, and the main outer shaft being supplied with driving means. 115

3. The combination with a circular cigarette cutting knife, of a carrier for the knife, means for producing a continuous orbital movement of the carrier, said orbit being of substantially circular contour, and means for varying the radius of the said circular orbit. 125

4. In a means for producing an orbital movement of the carrier of a circular cig- 130

- arette cut-off knife, the combination of two hollow and one solid shaft, including an outer main driving shaft, said main shaft being provided with a bore therethrough, 5 the axis of said bore being parallel to the axis of the main shaft but offset therefrom, a second shaft within the bore of the main shaft, and free to be rotated therein, said second shaft being provided with a bore 10 therethrough, the axis of said bore being parallel to the axis of second shaft but offset therefrom, a third shaft mounted in bearings within said second shaft and passing through said second shaft, and means 15 for rotating said second shaft on its axis for the purpose of adjusting the radius of the path of said orbital movement.
5. In a mechanism for producing an orbital movement of the carrier of a cigarette 20 cut-off knife, a means for adjusting the radius of said orbital movement including a set of three nested shafts, the outer two of the said shafts being provided with bores therethrough, and means for rotating the 25 intermediate shaft consisting of a worm gear on the periphery thereof, a screw mounted in the outer shaft, said screw being constrained against longitudinal movement in said outer shaft, and the threads of said 30 screw meshing with the teeth of the worm gear on said intermediate shaft.
6. In a cigarette cutting mechanism, a circular cut-off knife, a knife shaft, the knife mounted on said shaft, a driving pinion 35 mounted on said shaft, a main driving shaft, an intermediate shaft, an interior shaft, a bevel gear mounted on said intermediate shaft, the center of said bevel gear coinciding with the axis of said interior shaft, said 40 bevel gear meshing with said driving pinion, means for driving said main shaft whereby the bevel gear is rotated and thereby rotates the cut-off knife driving pinion.
7. In a cigarette cut-off mechanism, a circular knife, a carrier for the knife, means 45 for producing a continuous orbital movement of the knife carrier, a cross-bar comprising a vertical and a horizontal member, fixed guide bars adapted to receive the horizontal member of the cross-bar, whereby the cross-bar is constrained to reciprocate in a horizontal direction only, guide bars on the knife carrier and fixed thereto, the said guide bars adapted to receive the vertical member 55 of the cross-bar, whereby the horizontal component of the movement of the knife carrier is imparted to the cross-bar, a rod guide, a carrier for the rod guide, means for raising and lowering the rod-guide carrier, guide 60 bars on the rod-guide carrier and fixed thereto, said guide bars adapted to receive the vertical member of the cross-bar, whereby the rod guide in its vertical movement must be guided by the vertical member of the 65 cross-bar, the aforesaid combination adapt-
- ed to maintain the horizontal component of the movement of the rod guide at all times in unison with the horizontal component of the movement of the knife carrier, to the extent that the rod guide neither recedes from 70 nor approaches in a horizontal direction the knife at any period in the operation of the cut-off mechanism.
8. The combination with a cigarette rod guide, of a circular knife, a carrier for the 75 knife, a shaft for the carrier, mechanism for producing a continuous movement of the carrier, the carrier shaft and the knife in an orbital path about an axis at right angles to and offset from the guide, and means for rotating the knife including an operating member on the axis of said carrier shaft.
9. The combination with a cigarette rod guide, of a circular knife, a carrier for the 80 knife, a shaft for the carrier, means for producing a continuous movement of the carrier, the carrier shaft and the knife in a vertical orbital path about an axis at right angles to and offset from said guide, and means for rotating said knife including an 85 operating member on the axis of said carrier shaft.
10. The combination with a reciprocating cigarette rod guide, of a circular knife, a carrier for the knife, a shaft for the carrier, 90 means for producing a continuous movement of the carrier and the shaft together with the knife in an orbital path about an axis at right angles to and offset from the guide and in co-ordination with the reciprocating 95 movement of the guide, and means for rotating the knife including an operating member on the axis of the carrier shaft.
11. The combination with a reciprocating cigarette rod guide, of a circular knife, a 100 carrier for the knife, a shaft attached to the carrier, mechanism for producing a continuous movement of the shaft in a vertical orbital path about an axis at right angles to and above the guide and in co-ordination 105 with the reciprocating movement of the guide, and means for rotating the knife including an operating member on the axis of the carrier shaft.
12. The combination with a reciprocating 110 cigarette rod guide, of a circular knife, a carrier for the knife, a shaft for the carrier, means for producing a continuous movement of the carrier, the shaft and the knife about an axis at right angles to and offset from the 115 axis of said guide, means for rotating the knife including an operating member on the axis of the carrier shaft, and means for maintaining the plane of the knife and the axis of the guide in a right angle relation 120 throughout the movement of the carrier.
13. The combination with a cigarette rod 125 guide, of a circular knife, a carrier for the knife, a shaft for the carrier, mechanism for producing a continuous movement of the 130

- carrier about an axis at right angles to and offset from said guide, means for rotating the knife including an operating member on the axis of the carrier shaft, and means for adjusting the distance between the carrier and the rod guide, including a separable guide holder and carrier frame therefor, bolts in the guide holder and a slot in the guide carrier to receive the bolts. 50
14. The combination with a circular cigarette cut off knife, of a carrier for the knife, a shaft for the carrier, mechanism for producing a continuous movement of the carrier and knife in an orbital path, and knife 55
- rotating mechanism including a gear on the axis of the carrier shaft, said gear fixed to the bearing surrounding said shaft, a knife shaft mounted in the carrier at right angles to the axis of the orbital movement, and a 60
- pinion on said knife shaft in mesh with the gear surrounding the axis of the carrier shaft. 65
15. The combination with a reciprocating cigarette rod guide, of a knife, a carrier for 70
- said knife, means for producing a continuous orbital movement of the carrier in an orbital path about an axis at right angles to and offset from the axis of the guide, and in co-ordination with the reciprocating movement of said guide, a main driving shaft, a carrier shaft attached to the said carrier, the axis of the carrier shaft being parallel to the axis of the main shaft and offset therefrom, a bevel gear attached to said main 75
- shaft, the axis of said gear being coincident with the axis of said carrier shaft, a knife shaft, a bevel pinion of said knife shaft, said pinion meshing with said gear, the source of motion of said knife being derived 80
- from the motion of said main shaft through the planetary motion of the said gear and pinion. 85
16. The combination with a reciprocating cigarette rod guide, of a knife carrier, a shaft attached to said carrier, a knife shaft at right angles to said carrier shaft, a main driving shaft, the axes of said shafts being parallel but offset, said carrier shaft being 90
- free to turn on bearings in said main shaft, a bevel gear attached to said main shaft, the center of said bevel gear being in line with the axis of the carrier shaft, a pinion on the knife shaft, said gear and said pinion in mesh, said knife carrier being restrained from rotating but free to move in either a vertical or a horizontal direction, the axis of the knife shaft being maintained parallel to the axis of the rod guide, and means to rotate the main shaft whereby the knife shaft is rotated by the planetary movement of the 95
- pinion in an orbital path. 100
17. The combination with a circular cigarette cut-off knife, of a carrier for the knife, a carrier shaft pinned to the knife carrier, a main driving shaft, an intermediate shaft within said main shaft, the axis of the intermediate shaft being parallel to the axis of the driving shaft but offset therefrom, the said carrier shaft being within said intermediate shaft, the axis of the carrier shaft 105
- being parallel to the axis of the intermediate shaft but offset therefrom, a worm gear sector in the periphery of said intermediate shaft, and a worm screw journaled in said main shaft, the threads of said worm meshing with the teeth of the worm gear sector on said intermediate shaft for the purpose of rotating said intermediate shaft on its axis, and thereby varying the radial distance 110
- between the axis of the main shaft and the axis of the carrier shaft. 115
18. In a cut-off mechanism for cigarette machines, the combination with a circular cigarette cut-off knife, of a carrier for the knife, a reciprocating cigarette rod guide, means for producing a continuous movement of the knife carrier in a circular orbital path, said means including a main driving shaft, a knife carrier shaft fixed to said carrier and eccentrically mounted in said main shaft, and means for retaining the plane of said knife always at right angles to the axis of said rod guide. 120

In witness whereof, I have hereunto affixed my signature.

GEORGE A. WEINGARTNER.
